CLAIM

The ornamental design for a tricycle flower pot holder, as shown and described.

DESCRIPTION

FIG. 1 is a perspective view of a tricycle flower pot holder showing my new design;

FIG. 2 is a right side view thereof;

FIG. 3 is a left side view thereof;

FIG. 4 is a top view thereof;

FIG. 5 is a bottom view thereof;

FIG. 6 is a rear view thereof; and,

FIG. 7 is a front elevational view thereof.

The broken line showing of the tricycle seat is for illustrative purposes only and forms no part of the claimed design.
